US0D1063474S

(12) **United States Design Patent** (10) **Patent No.:** **US D1,063,474 S**
(45) **Date of Patent:** **** Feb. 25, 2025**

(54) **CHAIR**

(71) Applicant: **STEELCASE INC.**, Grand Rapids, MI (US)

(72) Inventor: **Kaitlyn Gillmor**, Grand Rapids, MI (US)

(73) Assignee: **Steelcase Inc.**, Grand Rapids, MI (US)

(**) Term: **15 Years**

(21) Appl. No.: **29/852,483**

(22) Filed: **Sep. 7, 2022**

(51) **LOC (15) Cl.** **06-06**

(52) **U.S. Cl.**

USPC **D6/716.4**

(58) **Field of Classification Search**

(57) **CLAIM**

The ornamental design for a chair as shown and described.

DESCRIPTION

FIG. 1 is a top front left perspective view of a chair of the present design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

Uniform broken lines show structure that forms no part of the claimed design.

1 Claim, 7 Drawing Sheets
